Inventor,
Benjamin J. Biddle.

UNITED STATES PATENT OFFICE.

BENJAMIN J. BIDDLE, OF MONTVILLE, NEW JERSEY.

COMBINATION TOOL.

Application filed April 18, 1922. Serial No. 554,863.

To all whom it may concern:

Be it known that I, BENJAMIN J. BIDDLE, a citizen of the United States, residing at Montville, in the county of Morris and State of New Jersey, have invented certain new and useful Improvements in Combination Tools, of which the following is a specification.

This invention relates to improvements in carpenters' tools and has for its object to provide means whereby an ordinary saw having a straight edge may be used as a carpenter's square.

Another object of the invention is to provide a combined saw and carpenter's square.

Another object of the invention is to provide a device which may be attached to an ordinary saw having a straight edge, whereby a carpenter's square may be provided.

With the above and other objects in view I have invented the device illustrated in the accompanying drawings in which—

Figure 1 is an elevational view of a saw embracing my invention;

Fig. 2 is a top edge view thereof;

Fig. 3 is a section on line 3—3 of Fig. 1;

Fig. 4 is an enlarged detailed perspective view of a square-forming attachment; and

Fig. 5 is a fragmental view of a pattern from which said attachment is formed.

Like reference characters indicate like parts throughout the following specification and in the several views in the drawings, in which 1 indicates a saw having a straight edge 2 and to which is attached a flange member 3, said member 3 being stamped from flat sheet-metal as indicated in Fig. 5, and having a clamp portion 4 formed at right angles to the flanges 5 and 6, said member 4 being U-shaped and adapted to straddle the saw blade adjacent the handle 7 of the saw and which is secured in place by means of rivets 8. The flanges 5 and 6 seat at right angles to the blade 1, whereby

said flanges together with the straight edge 2 form a square. As above stated, my device is originally a flat strip of sheet metal which is then bent up into angle-iron shape

with its flanges at right angles to the plane of the body portion, there being a small section of said flanges at an equal distance from each end cut away, which then allows the body portion to be folded to make a U-shaped strap.

The advantages of a device of this kind is very apparent, as two very important and essential carpenter's tools are provided in the one instrument, thus the carpenter is not only saved the trouble of looking for a square when he wants it, but is also saved the time necessary to change tools.

Having described my invention, that which I claim to be new and desire to procure by Letters Patent is:

1. In combination with a saw, flanges formed transversely to the blade thereof, said saw having a straight edge arranged at right angles to said flanges, and a U-shaped strap upon which said flanges are formed, said strap straddling the blade of said saw and being riveted in place thereon.

2. A device of the kind described, consisting of a U-shaped strap adapted to straddle a saw blade, each arm of said strap having a right-angular flange forming a short arm of a carpenter's square, and means whereby said strap may be fixed to said blade, whereby said short arms may coact with the straight edge of said blade to form said square.

3. A device of the kind described, consisting of an angle-iron, one flange of which is centrally cut out and the other flange bent upon itself over a saw blade to form a means whereby the device may be fixed to said blade, the spaced-apart members of said first flange each forming a short arm at right angles to the back edge of said blade, whereby said edge and arms form a carpenter's square.

In testimony whereof I affix my signature in the presence of two witnesses.

BENJAMIN J. BIDDLE.

Witnesses:

LOUIS CAYWOOD,
ALBERT O. MILLER.
